(57) **CLAIM**

The ornamental design for a juicer base, as shown and described.

DESCRIPTION

FIG. 1 is a perspective view of a juicer base, showing my new design;

FIG. 2 is a front elevation view thereof;

FIG. 3 is a rear elevation view thereof;

FIG. 4 is a side view thereof;

FIG. 5 is an opposing side view of FIG. 4;

FIG. 6 is a top plan view thereof;

FIG. 7 is a bottom plan view thereof; and,

FIG. 8 is the perspective view of FIG. 1 shown coupled to juicer components, the juicer components shown in broken lines and forming no part of the claimed design.

The broken lines in the drawings depict portions of the juicer base and environment, specifically the juicer components in FIG. 8, that form no part of the claimed design.
